DESIGN FOR AN AIR CONDITIONING CONTROL

Homer E. Malone, Milwaukee, Wis., assignor to
Perfex Corporation, Milwaukee, Wis., a corpo-
ration of Wisconsin

Application December 26, 1941, Serial No. 104,856

Term of patent 14 years

To all whom it may concern:

Be it known that I, Homer E. Malone, a citizen of the United States and a resident of Milwaukee, in the county of Milwaukee and State of Wisconsin, have invented a new, original, and ornamental Design for an Air Conditioning Control, of which the following is a specification, reference being had to the accompanying drawing, forming a part thereof.

Fig. 1 is a front view of an air conditioning control showing my new design;

Fig. 2 is a perspective view; and

Fig. 3 is a side elevational view thereof.

I claim:

The ornamental design for an air conditioning control, substantially as shown.

HOMER E. MALONE.
